UNITED STATES PATENT OFFICE.

CYRUS H. McCORMICK, JR., AND HENRY E. PRIDMORE, OF CHICAGO,
ILLINOIS, ASSIGNEES TO THE McCORMICK HARVESTING MACHINE
COMPANY, OF SAME PLACE.

GRAIN-BINDER.

SPECIFICATION forming part of Letters Patent No. 378,401, dated February 21, 1888.

Application filed May 29, 1885. Serial No. 167,106. (No model.)

To all whom it may concern:

Be it known that we, CYRUS H. McCORMICK, Jr., and HENRY E. PRIDMORE, both of Chicago, in the county of Cook and State of Illinois, have jointly invented certain new and useful 5 Improvements in Grain-Binders, of which the following is a specification.

In harvester-binders in which the grain is carried over the main wheel before being deposited upon the ground it has been usual heretofore to elevate it from the platform between endless aprons or by means of toothed rakes carried by endless chains and delivering to automatic binding mechanism upon the 15 outer side of said wheel.

In our invention we propose to locate a reciprocating binding attachment upon inclined ways between the main wheel and the inner end of the platform, dispensing with such elevator aprons or rakes, and binding the grain as the carriage traverses upward and outward toward the top of the wheel, so that at the end of the outward traverse the bound sheaf may be delivered from the binding attachment directly over said wheel and fall down a chute to the ground or into a bundle-carrier; and said invention relates, mainly, to such construction and its accessory mechanism, but also to various subordinate features, all as hereinafter 30 described and claimed.

In the drawings, Figure 1 is a perspective view, from the front, of a harvester-binder embodying our improvements, the platform apron being removed; Fig. 2, a top plan view with 35 certain essential parts not shown in the preceding figure, to expose more clearly the features of our invention; Fig. 3, a rear elevation of said machine; Fig. 4, an enlarged view in elevation, from the rear, of the binding attachment and tripping devices, with certain of the pinions and gear-wheels shown in the preceding figure omitted to expose the tripping-clutch; Fig. 5, an enlarged detail in top plan of the elevating and packing drums at the inner end of the platform-apron, and Fig. 6 a transverse section therethrough on the scale of the preceding figure.

A is the rear still, and A' the front sill, of the harvester. B is the platform-apron, and C is the 50 main carrying and driving wheel, adjustably

supported in the usual manner and at the distance from the inner end of the platform-apron customary when elevator-aprons are used. From these sills rise struts or standards D, which form the substructure of a strong frame, 55 D', extending from the outer side of the wheel to a point about over the inner end of the platform-apron and steadied by a brace, D'', from the outer end of the rear still. This frame supports the seat D'', the reel-driving 60 shaft, and the various levers and controlling devices by which the reel-frames and the tongue are operated.

Between the main-wheel and the inner end of the platform-apron is the binder-supporting 65 frame E, having feet e, which slide upon ways e', mounted upon cross-timbers of the main frame, the outer way, adjacent to the wheel, being for convenience secured to the inner lateral timber, E', of the wheel-frame, and the 70 inner way being secured to a bar, E'', connecting the front and rear sills at a lower elevation, in order that the frame shall be inclined toward the top of the sill. From the rear of the binder-frame projects a rack-bar, e'', with which engages a pinion, e', at the lower end or foot of a shaft, e', having a crank at its upper end within convenient reach of the driver in his seat, whereby this binder-frame may be adjusted back and forth on its ways to compensate 75 for varying lengths of grain.

Attached to the binder-frame, so as to move back and forth with it, is a wind-board, F, from which projects a bar, f, overhanging the rear of the platform and carrying a pendent 85 screen, F', that extends down nearly to the platform-apron and corresponds in length thereto, and which will be moved to the front or rear with the wind-board on the binder when the binder-frame is adjusted, so as to prevent grain 90 being cast too far back by the reel or blown off the platform by the wind. To better sustain the platform-screen and prevent sagging, its supporting-bar rests upon the upper edge of a board or cross-piece, F'', connecting the front 95 and rear inner struts for the superstructed frame, and slides thereon as on a way in its adjustments back and forth.

Upon the binder-frame are ways g, such as usual in the McCormick reciprocating binder, 100

which, like the frame itself, are directed slantingly upward toward the head of the main wheel, and upon these ways is supported the reciprocating carriage G, carrying a frame or 5 standard, G', with an overhung arm, g', in which is journaled a rock-shaft, g², having a binder-arm, G², at one end and a crank, g³, at the other. Brackets on this overhung arm, also support the compressor G³ and bridge-arm 10 G⁴, both of which in their peculiar relation to the binder-arm and the mode of operating them are the inventions of Henry E. Pridmore, and have been made the subject of an independent application by him filed in the 15 Patent Office of the United States on the 16th day of March, 1885, Serial No. 159,078, and are here shown only for the purpose of explaining the principle of our invention, and not as being in their specific form necessary 20 thereto.

The binder-carriage also has in its subtending arm, which passes beneath the decking or binding-table, a shaft, H, bearing a loose pinion, h, at its outer end, which meshes with 25 a rack, H', alongside the adjacent way of the supporting-frame and is clutched to the shaft in the outward traverse by means of a dog, h², so as to drive it, and through it operate the grain securing, holding, and severing 30 devices, but is unclutched therefrom in the inward traverse, all as more fully explained in the above-mentioned application.

At the inner side of the binder-frame is mounted another shaft, I, which bears a gear-wheel, I', having a wrist-pin, i, near its outer periphery. From this wrist-pin a pitman, I², extends to the subtending shaft in the binder-carriage and is collared thereto, so that as the 35 wheel revolves the carriage may be alternately 40 pushed up the inclined ways and drawn or permitted to slide back. The pitman has also an upwardly-extending arm, I³, which bears at its end a stud or anti-friction roller, i², entering a cam-shaped slot, i³, in and trending transversely of a link, I⁴, which is connected to the crank from the binder-arm shaft and adjustable in length, as usual. The lower end of this 45 link has also a slot, i⁴, which is, however, this time straight and nearly longitudinal, but yet 50 slightly inclined to the length of said link, and which receives a stud or anti-friction roller, i⁴, from the body of the pitman. The effect of this arrangement is that as the pitman is thrust against the binder-carriage and moves it upward, and its heel is gradually raised by the 55 revolution of the gear-wheel to which it is connected, the link from the binder-arm shaft is held against lateral play by the stud from the pitman entering the longitudinal slot therein, 60 while the upper stud, or the one at the end of its branch arm, rides in the inner curved reach of the cam slot and holds it against vertical play, or rather moves it slightly downward relatively to the rising pitman, thus keeping 65 the binder-arm down alongside the binding mechanism until the outer traverse is completed, when the upper stud passes out of said

reach and into the adjoining reach, being permitted to do so by the play of the lower stud in the longitudinal slot, and the binder-arm 70 and compressor are rapidly opened to release and discharge the bound sheaf. In the return traverse the binder-arm is held up or open until the inner side of the platform is reached, and in this construction the carriage is intended to stop with the arm thus opened at said inner side, the mechanism being unclutched from the harvester-gearing with the arm in this position. However, if the tripping mechanism is dispensed with it will be immediately 80 closed by the continued revolution of the gear-wheel, carrying the upper stud into the inner reach of the cam-slot once more and forcing it down thereon.

For the purpose of unclutching the gear-wheel from its driver, as just intimated, the usual tripping-clutch employed in the McCormick binder may be used; but we have shown one invented by Henry E. Pridmore, and made the subject of a patent granted him August 18, 1885, No. 324,786, which is particularly adapted to the inclined movement of the binder-carriage, since a large part of the weight of the latter must be supported by the gearing in the outward traverse and in the return movement 95 as well. To form this clutch, a loose pinion, K, is mounted upon a constantly-driven shaft, k, in the harvester-frame. Alongside this pinion is geared a disk or cross-head, K', having studs k' projecting toward the pinion, and to the pinion itself, on the side facing the cross-head, is pivoted a dog, K², having a lever-arm, k², and pressed out into normal engagement with one or the other of the driving-lugs of the cross-head by means of a spring, k', secured to the pinion. The engagement of the driving-lug with this dog serves to drive the pinion, and through it the gear-wheel, and move the carriage, but does not insure against either backlash or running ahead, and therefore a second dog, K³, is pivoted to the pinion in a position reverse to that of the first, and provided with teeth on its hub meshing with teeth on the hub of the other, so that whenever the first is thrown into engagement it 110 will throw the second or locking dog into engagement also with the opposite stud and on the same side of that stud as the engagement of the driving-dog with its stud. The pinion will be by this means locked positively to the 115 cross-head and the evils referred to will be 120 obviated.

In order to disengage the driving and locking dogs from their lugs, or the driving-dogs alone, if no lock-dog is used, a trip-latch, L, 125 is pivoted to the inner end of the binder-frame, adjacent to the gear-wheel, in such position that its ends may be thrown into the path of the lever-arm from said driving-dog and stop it, moving the dog on its pivot and closing it 130 in toward the shaft, when the lugs on the cross-head will run past it without actuating the pinion. As soon, however, as this latch is removed from contact with the lever-arm, the

dog will spring into engagement with the nearest approaching lug, and the binding mechanism will be started.

From the end or engaging portion of the latch rises an arm or finger, l , connected by a link, L' , with a crank-arm, l' , from a rock-shaft, l^2 , to which is fixed a tripping arm or lever, L^2 , so arranged as to come about the center or waist of the gavel of grain delivered to it. Normally this arm is down, with its point touching or nearly touching the decking of the binding-table; but as the grain is delivered to it and packed against it, by whatever means, it is forced back and gradually rises, rocking the shaft, and finally pushing the latch out of contact with the driving-dog, allowing the clutch to engage to start the binding mechanism.

In order that the starting may be determined by a greater or less accumulation of grain, as desired, the link which connects the trip-latch to the crank-arm from the tripping shaft is provided with a series of perforations, l^3 , which enable it to be lengthened or shortened between the latch and the crank-arm, throwing the tripping arm or lever farther back from or bringing it nearer to the delivery-point of the grain, and permitting a greater or less accumulation of grain before said arm is actuated.

If the tripping-latch were left to itself after the binder had taken the gavel from beneath the tripping-arm and started on its outward traverse, the weight of said arm would carry the latch back into the path of the driving-dog, and this dog would strike against it the first time it came around and unclutch the mechanism, probably before the traverse was half-finished. To prevent this the latch is provided with a heel-extension, l^4 , having an anti-friction-roll, l^5 , which, as soon as the gear-wheel is started, begins to travel on a cam-ledge, l^6 , about the hub of said wheel, thereby holding the latch away from the driving dog until the end of the return-traverse, when it falls off the end of the ledge and at once meets the driving-dog and brings the mechanism to a stop.

Above the tripping lever is pivoted a curved arm, M , the end of which rests by its own weight or by slight spring-pressure upon the binding-table beyond the end of said lever, and which is intended to retain the gavel released by the yielding of the lever and keep it shapely until the binder-arm and compressor have had time to come down and gather it.

No special form of packing devices is essential to the operation of our tripping mechanism; but in order to increase slightly the elevation of the binder-frame at its inner side we have thought it preferable to employ the structure shown in Figs. 5 and 6, consisting, essentially, of a rotating drum having rocking or oscillating shafts armed with teeth, which lift the grain from the delivery end of the platform-apron and carry it up and pack it against the tripping-lever. To more particularly explain this, a constantly-rotating shaft at the inner end of the platform, and herein

shown as the same shaft which carries the loose pinion or tripping-clutch, is armed along its length with disks or spider-frames N , the end ones of which have bearings n for a series of rock-shafts, N' , and the middle one of which serves to support and brace said shafts against sagging. At certain distances along their length these shafts have teeth n' , while at one end they are provided with crank-arms $n^2 n^3$, one of the crank-arms having a long stud, n^4 , armed with an anti-friction roller, and the other a short lateral stud, n^5 , which may be similarly armed, but is shown without a roller.

To the frame, at the adjacent end of the machine, is secured a cam-plate, O , which has trackways $O' O^2$ for these studs, the latter projecting farther than the other to catch the roller on the short stud.

The grain is delivered by the platform-apron A' into a cradle formed by standards O^3 , secured to the frame-work, having vertical shanks and curved offsetting arms or fingers, which at one end are in close proximity to the apron, while at the other they nearly touch the curved guide-bands O^4 above the drum. Now, as the shaft revolves the longer roller on the crank-arms of the shafts which it carries travels in the trackway O' , and at first as it passes along the reach o of their trackway, which reach is but slightly eccentric to the axis, the teeth are projected between the shanks of the cradle-fingers and then swung instantly up to lift the grain thereon, becoming at the moment horizontal or inclined a little upward. In this position they are carried up nearly radial to the axis of revolution until the roller arrives at the end of this reach, when it enters a second reach, o' , inclining inward and toward the center of the cam-plate, and therefore relatively depressing the roller and throwing the lifting-fingers slightly back, or rather keeping them vertical, until finally, just before the end of this reach, the shorter stud on the other crank-arm strikes the raised track o^2 , and as the anti-friction roller on the longer arm emerges from its own camway tilts the fingers back and causes them to be withdrawn from the grain without obstruction. As the fingers rock back, the short stud leaves the track o^2 , and the anti-friction roll on the longer stud enters another reach, o^4 , and swings them still farther back or inward until their points are nearly radial to the axis of rotation, so as to be out of the way. As the roller approaches the end of this reach, it enters a short curved extension, o^5 , thereof, and at that moment the stud on the opposite arm strikes a flange, o^6 , serving to direct the anti-friction roller against a stop-ledge, o^7 , immediately at the entrance of the starting-reach. This affords an obstruction or bar which oscillates the tooth-shaft and swings the short stud up and over, as shown at the foot of Fig. 6, bringing the tooth again in its starting position, projecting between the shanks of the cradle-fingers.

The trajectory described by the point of the tooth in the movements just described is in-

dicated in dotted lines in the figure last referred to. The movements of the series of teeth on the successive shafts carry the grain up in wisps or handfuls and force it under the compression-springs P and into the space determined by the position of the trip-lever, packing it against said lever until sufficient has accumulated to form a gavel of the desired size, when the pressure will cause the lever to yield, releasing the trip-latch and permitting the binding mechanism to be started. The carriage will then start on its outward traverse, the binder-arm will come down, carrying the band material around the gavel thus accumulated and to the grain-securing mechanism, and immediately thereafter the subtending shaft in the carriage will engage with its pinion and begin to operate said securing mechanism. At the end of the outward traverse the sheaf will have been securely bound, and as the binder-arm rises it will be discharged over the head of the main wheel and fall down the chute or into a bundle-receptacle to be carried until sufficient has accumulated to form a gavel.

We claim—

1. The combination, substantially as hereinbefore set forth, of the platform apron or carrier, the main wheel, the reciprocating binder-carriage intermediate between the delivery end of the carrier and the main wheel, the tripping-lever at the inner end of the binding-table, and packing mechanism immediately at the delivery end of the platform-carrier to force the grain against said tripping-lever and start the carriage.

2. The combination, substantially as hereinbefore set forth, of the platform apron or carrier, the main wheel, the binder-frame intermediate between said carrier and the main wheel and having ways inclined toward the top of said wheel, the binder-carriage reciprocating upon said ways, the tripping-clutch by which the mechanism actuating said carriage in its movements is set in motion, the tripping-lever connected to said clutch, and the packing-rakes or drum elevating the grain from the delivery end of the carrier to the lower and inner end of the binding-table and packing it against the tripping-lever.

3. The combination, substantially as hereinbefore set forth, with the platform apron or carrier and a binder-frame adjustable transversely of the machine, of a wind-board at the rear of said binder-frame and a screen at the

rear of the platform, both supported by and from the binder-frame, whereby they partake co-ordinately of its adjustments.

4. The combination, substantially as hereinbefore set forth, in a harvester-binder, of a platform apron or carrier, a main wheel, a binder-frame intermediate between said carrier and the main wheel, ways upon which said binder-frame is adjustable back and forth transversely of the platform-apron, a screen or wind-board for the rear of the platform suspended from an overhung arm attached to the binder-frame, and a support or slide-rest for said arm between the binder-frame and the screen.

5. The combination, substantially as hereinbefore set forth, with the reciprocating binder-carriage and the vibrating binder-arm carried thereby, of the gear-wheel at the inner end of the binder-frame, the pitman connecting a wrist-pin thereon with the binder-carriage, an upright arm or fork from said pitman, studs or anti-friction rolls carried by the pitman and by said arm or fork, the crank from the binder-arm shaft, and the link having oblique and cam-shaped slots into which said studs take, whereby the proper motions are given to both the binder-carriage and the binder-arm by said pitman.

6. The combination, substantially as hereinbefore set forth, to form a grain feeding or packing drum, of the revolving shaft, the disks or spiders carried thereby, the oscillating shafts carried in bearings in said disks and having teeth, the two crank-arms at the ends of said shafts, the cam-plate, and the cam-tracks having the outline shown and described.

7. The combination, substantially as hereinbefore set forth, with the reciprocating binder-carriage, the binder-arm and compressor carried thereby, and with the tripping-lever by which said carriage is started, of the retaining-arm which receives and retains the gavel until the descent of binding-arm and compressor after the tripping-lever yields and starts the machine.
